UNITED STATES PATENT OFFICE.

FRANK C. FAURE, OF PETALUMA, CALIFORNIA.

AUTOMATIC SPARK RETARDER.

Application filed September 13, 1923. Serial No. 682,536.

To all whom it may concern:

Be it known that I, FRANK C. FAURE, a citizen of the United States of America, residing at Petaluma, in the county of Sonoma and State of California, have invented certain new and useful Improvements in Automatic Spark Retarders, of which the following is a specification.

This invention relates to automobiles, and 10 has special reference to a safety device for automobile engines in the nature of an automatic spark retarder.

It is a well known fact that practically all automobile engines are provided with a 15 starting motor which is controlled by a switch convenient to the operator's foot.

It is also well known that the engines of automobiles, of the internal combustion type, should always be started with the 20 spark retarded as if an attempt is made to start the engine with the spark advanced, the engine is apt to kick back and injure the starting motor, or the person cranking the engine where a crank is used.

25 The principal and most important object of the present invention is to provide an automatic means whereby, prior to the possibility of closing the starting switch, it will be necessary to move the spark retard- 30 ing element to spark retarded position.

A second important object of the invention is to provide a novel and improved device actuated by the same movement on the part of the operator which closes the start- 35 ing switch to primarily retard the spark.

A third important object of the invention is to provide an improved means of the foregoing description which will permit 40 retarding of the spark in the usual manner by the operator without interfering with the automatic spark retarding means.

With the above and other objects in view as will be hereinafter apparent, the invention consists in general of certain novel details of construction and combinations of parts hereinafter more fully described, illustrated in the accompanying drawings and 45 specifically claimed.

In the accompanying drawings like characters of reference indicate like parts in the several views, and:

Fig. 1 is a side elevation of the device shown in its relation to the controlling switch of the starting motor, and to the 50 spark retarding element.

Fig. 2 is a front view thereof.

Fig. 3 is an enlarged detail view showing the yielding arrangement for permitting operation of the ordinary spark retarding lever without operation of the automatic 60 means.

Fig. 4 is a section on the line IV—IV of Fig. 3.

In carrying out this invention, in the embodiment herein illustrated, there is provided a pair of bearings 10, secured on the foot board 11 of the automobile, and in these bearings is journalled a rock shaft 12 having projecting from one end a rock arm 13 provided at its extremity with a 70 pedal 14, which overlies the starting switch S, but is normally in spaced relation thereto. From the other end of the rock shaft 12 extends a rock arm 15, and it is to be noted that the rock shaft and its two rock 75 arms are preferably formed integrally with a single length of rod. This last rock arm 15 is provided at its extremity with an opening 16 wherethrough passes a rod 17 projecting rearwardly from the arm 15, 80 and surrounded by a coiled compression spring 18 which is held in tension adjusted position on the rod by the nuts 19. On the forwardly projecting end of this rod 17 is a push bar 20 which has one end 85 turned laterally as at 21 to receive the rod 17 and to form a bearing against which the arm 15 pushes. The other end of this bar 20 is also turned laterally as at 22, and enters an eye 23 on a connecting mem- 90 ber 24 clamped to the spark controlling ele- 95 ment 25, this being here shown as a rod and having the usual connection, (not shown) with the arm on the distributor.

Now in operation it will be seen that when 95 it is desired to start the car by means of the switch S, the operator places his foot on the pedal 14 and depresses this pedal. The effect of this is first to move the spark to retarded position, and then to close the 100 switch S. Thus the spark is always retarded whenever the switch S is closed. If the operator desires to retard the spark, as in running, he may do this without affecting the position of the pedal since the spring 18 105 will yield and permit the rod 17 to slide through the end of the rock arm 15.

While the device has been shown in this particular instance as mounted on a foot board, it is obvious that it is mounted in 110

whatever position is convenient to the switch S, it being noted that different cars have the starting switches in widely different positions.

5 There has thus been provided a simple and efficient device of the kind described, and for the purpose specified.

It is obvious that minor changes may be made in the form and construction of the 10 invention without in any way departing from the material spirit thereof. It is not, therefore desired to confine the invention to the exact form herein shown and described, but it is wished to include all such as 15 properly come within the scope claimed.

Having thus described the invention, what is claimed as new, is:

1. The combination with the starting motor switch and the spark control element 20 of an automobile engine; of means connected to the control element and operable primarily to move the control element to spark retarding position and then to engage and close said switch, including a pedal 25 resting over the switch in normal spaced relation thereto, an operative connection between said pedal and spark control element, and provided with yieldable means to per-

mit retarding movement of the spark control element independently of the movement 30 of the pedal.

2. The combination with the starting motor switch and the spark control element of an automobile engine; of means connected to the control element and operable 35 primarily to move the control element to spark retarding position and then to engage and close said switch and including a rock shaft journalled adjacent said switch, a rock arm extending from said rock shaft and having a pedal overlying said switch in normal spaced relation thereto, a second rock arm extending from said shaft, a push bar having one end resting against the second rock arm to be moved thereby upon the pedal 40 being depressed, an operative connection between the remaining end of said bar and the spark control element, a rod projecting from said pusher bar through said second rock arm, a stop on the end of the rod, and a compression spring between said stop and the rock arm to hold the end of the pusher bar yieldably against the second rock arm. 45

In testimony whereof I affix my signature.

FRANK C. FAURE.
